CLAIM

The ornamental design for pair of earphones, as shown and described.

DESCRIPTION

FIG. 1 is a perspective view of the right earphone of a pair of earphones showing our new design;

FIG. 2 is a perspective view of the left earphone of the pair of earphones shown in FIG. 1;

FIG. 3 is a back perspective view of the right earphone shown in FIG. 1, with the left side being a mirror image thereof;

FIG. 4 is a front view of the earphone shown in FIG. 1;

FIG. 5 is a front view of the earphone shown in FIG. 2;

FIG. 6 is a top view of the earphones shown in FIGS. 1 and 2, shown together and connected; and,

FIG. 7 is a bottom view thereof.

The broken lines depict environment that forms no part of the claimed design.
